CLAIM

The ornamental design for a sliding panel handle assembly, as shown and described.

DESCRIPTION

FIG. 1 is a perspective view of a sliding panel handle assembly, showing my new design;

FIG. 2 is a front view thereof;

FIG. 3 is a left side view thereof;

FIG. 4 is a right side view thereof; and,

FIG. 5 is a top view thereof, with the bottom view, not shown, is a mirror image of the top view shown in FIG. 5. The bottom view, not shown, is a mirror image of the top view shown in FIG. 5;

The broken lines in the drawings illustrate environmental subject matter that forms no part of the claimed design.
